UNITED STATES PATENT OFFICE.

WILLIAM F. WAMSLEY, OF WALLA WALLA, WASHINGTON TERRITORY.

ELECTRICAL CONTACT DEVICE FOR HOSE-COPLERS.

SPECIFICATION forming part of Letters Patent No. 364,559, dated June 7, 1887.

Application filed November 2, 1886. Serial No. 217,797. (No model.)

To all whom it may concern:

Be it known that I, WILLIAM F. WAMSLEY, a citizen of the United States, residing at Walla Walla, in the county of Walla Walla 5 and Territory of Washington, have invented certain new and useful Improvements in Electric Contact Devices for Hose-Couplers; and I do hereby declare the following to be a full, clear, and exact description of the invention, such as will enable others skilled in the art to which it appertains to make and use the same.

This invention relates to an improvement in the construction of electrical conductors which 15 are used in combination with air-brake pipes and couplings for railway-cars for lighting and signaling; and my improvement has especial reference to those parts of the conductors which are inside of the tubular couplings 20 for the said pipes.

The coupling itself, which I shall hereinafter refer to, is shown in my joint application with Thomas McIntosh, marked "Case A," Serial No. 217,796, and bearing even date with 25 the filing of this, and not herein broadly claimed.

My present object is to simplify the construction and manner of insulating electrical contact-points inside the couplers, as will be 30 fully understood from the following description and claims, when taken in connection with the annexed drawings, in which—

Figure 1 is a vertical longitudinal section taken centrally through one of the tubular 35 couplers, showing my improvement applied to it. Fig. 2 is a vertical transverse section through the coupler, taken in the plane indicated by dotted line $\alpha\alpha$ on Fig. 1, looking toward the rear of the coupler. Fig. 3 is a top 40 view showing the improved contact-points secured to a grooved insulating-ring. Fig. 4 is a perspective view of one of the angular T-shaped headed contact-points, showing a binding-screw applied to it. Fig. 5 is a perspective 45 view of the recessed ring without the contact-points.

Referring to the annexed drawings by letters, A designates in section one of the couplings, to which a flexible air-conducting tube, pipe, 50 or hose, B—such as the ordinary Westinghouse air-brake hose—is attached in any suitable

manner. This coupling is constructed with a hollow case, C, into which is screwed a cap, D, having bearing-prongs a , that bear against a packing-ring, b , of leather or other suitable substance. The face c of the case is flat, and through it is a circular aperture, through which extends an elastic packing-ring, E, which in cross-section is of an L shape. The base of this ring lies in a circular rabbet, d , and the lip ec thereof is exposed beyond the surface c , as shown in Fig. 1. This ring not only serves in part as an insulator for certain electrical conducting-points hereinafter described, but it also serves, in combination with a similar packing-ring applied in the same manner to another coupler similarly constructed and provided with the contact-points insulated by a ring, to form an air-tight joint between two couplers.

F F are two angular contact-points oppositely arranged upon the ring G^2 , hereinafter described, and which may be made of any suitable metal, and which are respectively constructed with T-shaped heads ee , presenting broad contact-surfaces formed on angular portions ff , terminating in perforated shanks gg . Each contact-point or knee is provided with a binding-screw, H, adapted to receive and to have electrically connected to it the bare end of an insulated electric wire, one wire of one 80 point representing the positive pole of a battery and the other wire attached to the other point representing the negative pole of the battery.

G^2 designates a flat ring, which is clearly 85 shown in Fig. 5, and which is preferably made of india-rubber, though it may be made of any other suitable non-conductor of electricity. This ring G^2 is recessed at hh , and it is deeply 90 grooved radially at ii . It lies between the base-flange of the flanged packing-ring and the leather packing-ring, both of which are insulators. In practice the recessed ring G^2 is 95 preferably made of vulcanized rubber, although it may be made of glass. To it I secure in any suitable manner the two metallic points F F, which are placed far enough apart to prevent sparking, and their shanks or bases being so completely insulated that the current from the electrical source will not be dissipated through the couplings.

The wires which are connected to the posts

or binding-screws H are passed through the deep groove i of the non-conducting ring G² and carried to the battery through the interior of the flexible hose.

5. In practice the horizontal parts of the T-shaped limbs of the contact-points will be laterally rounded, so that in the act of making a coupling similar contact-points will lie closely with each other and form electrical connections between cars when a coupling is effected.

Having described my invention, I claim—

1. An air-brake hose-coupling containing an electrically non-conducting ring recessed and grooved radially, in combination with opposite contact-points secured to said ring, substantially as described.

2. In an air-brake hose-coupling, the combination of a packing and insulating ring and electrical contact points secured to opposite sides of said insulating-ring, to which the conducting-wires are secured and confined within the coupling between said ring and packing, substantially as shown and described.

3. In an air-brake hose-coupling, the insulating-ring having arranged at opposite sides 25 the bent arms F, provided with contacts e, said ring being grooved radially and seated within the coupling, and the packing-ring E, all arranged substantially as shown and described.

4. In an air-brake hose-coupling, the combination of the elastic flanged electrically non-conducting packing-ring E, a non-conducting ring, G², having oppositely-arranged contact-points and adapted to receive radially through 35 it the electric wires, and a non-conducting packing-ring, b, held in place by the screw-cap D, having bearing-prongs a, substantially as described.

In testimony whereof I affix my signature 40 in presence of two witnesses.

WILLIAM F. WAMSLEY.
